UNITED STATES PATENT OFFICE

JAMES W. SMALL, OF CHICAGO, ILLINOIS, ASSIGNOR OF ONE-HALF TO ELMER W. PAHLKE, OF CHICAGO, ILLINOIS

DESIGN FOR A VENDER'S TRAILER

Application filed January 18, 1932. Serial No. 42,528. Term of patent 14 years.

To all whom it may concern:

Be it known that I, JAMES W. SMALL, a citizen of the United States, residing at Chicago, in the county of Cook and State of Illinois, have invented a new, original, and ornamental Design for Venders' Trailers, of which the following is a specification, reference being had to the accompanying drawings, forming part thereof, showing my new design.

Fig. 1 is a perspective view of a vender's trailer showing my new design, and

Fig. 2 is a rear fragmentary elevational view of the upper part of the trailer looking in a general direction from the left in Fig. 1.

I claim:

The ornamental design for a vender's trailer as shown.

JAMES W. SMALL.
